LABEL APPLYING MECHANISM

George W. von Hofe, Bound Brook, N. J., assignor
to New Jersey Machine Corporation, Hoboken,
N. J., a corporation of New Jersey

Application August 14, 1950, Serial No. 179,109

9 Claims. (Cl. 216—21)

1

This invention relates to labeling machines, and more particularly to the means in such machines for applying labels or the like to the articles to be labeled.

Labeling machines of the type with which this invention is concerned, are designed for labeling articles of varying classes and dimensions. While the labeling machines heretofore made are generally successful in accomplishing the purposes for which they are designed, such success depends to a large extent on the fact that the articles on which they work, are structurally rigid, particularly in the case of containers. As a result, present day labeling machines cannot satisfactorily label containers made of flexible material such as for example, bottles made of a flexible polyethylene material of the type now coming into general use in the manufacture of containers.

The principal object of the present invention is to provide means whereby containers such as bottles made of flexible material can be satisfactorily and successfully labeled.

The foregoing object is achieved in accordance with the invention by providing means for temporarily rigidifying the portion of the container to which the label is to be applied, and then with a uniform pressure affixing to such surface portion a label coated with an adhesive which when dry, does not become hard and brittle, but remains flexible and which in its dry state, becomes inseparably bonded to the material of the container.

It is believed that a better understanding of the invention as well as its objects and advantages will be had after a perusal of the following description when read in connection with the accompanying drawings in which Fig. 1 is a diagrammatic view, partly in section, illustrating one manner in which the invention may be practiced; Fig. 2 is a sectional view taken along the line 2—2 of Fig. 1; Fig. 3 is a view similar to Fig. 2, but showing the label applying parts in closed condition; Fig. 4 is a partial schematic view showing another manner in which the invention may be carried out, and Fig. 5 is a schematic view illustrating another method of carrying out the invention.

In the drawings, the numeral 10 designates generally, a bottle made of polyethylene material and having side walls of such flexibility that they give under relatively small pressures, and may readily be squeezed to bring diametrically-opposed portions thereof into contact. In effect, the bottle has the same rigidity as if it were

2

made of a flexible rubber compound and substantially exhibits the same physical characteristics as a rubber bulb of like form.

The bottle 10 is deposited on a suitable support 5 at the label applying station of a label applying machine of any well known type, such as the labeling machine described and illustrated in the Von Hofe Patent No. 2,227,816, issued January 7, 1941. In such a machine, there is provided a 10 transfer means for the labels in the form of a suction head which successively carries labels from a source of supply to the label applying station of the machine. At the label applying station, the suction head is lowered to apply 15 the label carried thereby to the article; the suction in the head being so controlled that when the label is deposited on the article, such suction is released. As is shown in Fig. 1 of the drawings and explained more fully in said Patent No. 2,227,816, the mechanism for accomplishing this operation may include a carriage 12, which is slidably mounted on a rail 13 and is reciprocated on such rail by mechanism exemplified by the rod 14 and the arm 15; such rod 14 being pivotally connected at 16 with the carriage 12 and at 17 with the arm 15. A member or 20 plunger 18 is mounted on the carriage for vertical reciprocation thereon by suitable means in properly timed relation with the associated elements, and at its lower end carries the transfer device or suction head generally designated 19. In the 25 operation of this mechanism, the carriage 12 is reciprocated on the rail 13 to carry the suction head 19 between the pick-up station where a label is picked up and the label applying station 11, where such label is applied to the article for which it is intended, such as the bottle 10. It will be understood that in the operation of this mechanism, the plunger 18 is operatively 30 controlled to correspondingly control the operative steps of the suction head 19.

In practicing the invention, the labels may be of any desired form or dimensions, and may have any suitable type of adhesive coating provided 35 on one surface thereof. I have found however, that in order to obtain the best labeling results in accordance with this invention, the adhesive coating on the label should be composed of a heat activatable thermoplastic material, as such adhesive coating retains a degree of flexibility, which enables it to bend with the label covered portion of the article without rupture of its bond with the latter. Furthermore, when the article is made of substances such as are formed from 40 polyethylene materials, the thermoplastic ad-

hesive material becomes in effect, an inherent part of such substances, so as to permanently bond the label to the article, particularly when the label is applied under pressure with heat. The labels may either be fed from a supply stack directly to the label applying station such as is disclosed in my Patent No. 2,489,837, issued November 29, 1949, or connected in the form of a continuous web 21, which is wound into a roll 22 so that the surfaces thereof to which is applied the thermoplastic adhesive coating, are disposed to the periphery of such roll, as shown in Fig. 1 of the drawings. In the illustrated form of the invention, the roll 22 is supported by a shaft 23, which is mounted in the machine in any suitable manner to permit the roll 22 to unwind during the operation of the machine. The web 21 is fed towards the pick-up station 20 in any suitable manner, as by feed rollers 24, 24, operated intermittently in steps dependent upon and corresponding to the longitudinal dimension of the labels. At the pick-up station 20, the machine is provided with a support 25 over which the web is fed and associated with such support are suitable operating means 26, 26 to separate the individual terminal labels 27 from the web 21 when a terminal label 27 is properly positioned on such support. The arrangement and operation of the feeding and cutting mechanism are such that the individual labels 27 are deposited on the support 25 in accurate label receiving relation with the suction transfer head 19 and with the thermoplastic adhesive coatings thereof overlying a plurality of perforations provided in the upper surface of such support. The said perforations communicate with a chamber 28 which is connected by means of a tube 29 with a source of air. Suitable means are provided to produce a condition of suction in chamber 28 after a terminal label 27 has been deposited thereon, and to deliver compressed air into such chamber to blow the separated label 27 into contact with the suction head 19, when the latter is properly positioned in an at-rest position just above the label, as is shown. The suction in the head 19 is controlled by properly timed valving mechanism of any suitable type so that at the time the label is transferred by air pressure from the support 25 to such head, suction will be effective in such head to maintain a label properly in position thereon and until it is deposited on an article. The head 19 preferably carries a heating device composed of one or more electrical resistance elements which are mounted in such head and which are connected with a source of electricity by wires 30, 30, so that by the time a label has been carried by such head to the label applying station 11, the thermoplastic coating on such label has been adhesively activated.

After a label 27 has been deposited on the article 10 at the label applying station, means come into operation to complete the application of such label to the article. As will be observed from Figs. 1 and 2 of the drawings, the support 11 at the label applying station is recessed to provide a seat 35 for the accommodation of the bottle 10. It will be noted that the arc of curvature of the seat 35 in a transverse direction has a radius greater than that of the body of the bottle and is less than a semicircle so that the body of the bottle seated therein does not snugly fit in such seat and the longitudinal axis of such body is located above the upper edges of such seat for a purpose, which will hereinafter become more

clear. The support 11 may be mounted in the labeling machine as shown in the aforesaid Patent No. 2,227,816. Cooperating with the support 11, is a pressure member 36 depending from a member 37 which is vertically actuated in operative synchronism with the other parts of the machine in any suitable manner, as by the mechanism described and illustrated in the previously mentioned Patent No. 2,227,816. The pressure member 36 is provided with a seat 38 substantially similar to seat 35 in support 11. The pressure member 36 carries a heating device composed of a pair of electrical resistances 39, 39, which are connected with a source of electricity by the wires 40, 40 and which may be controlled by a thermostat 41 to maintain the pressure member 36 at a predetermined, uniform temperature.

It will be understood from the foregoing, that in the operation of the machine, and after a label has been deposited on the bottle 10 by the suction head 19, the member 37 is moved downwardly to thereby move the pressure member 36 into engagement with the bottle, as shown in Fig. 2 of the drawings. As the members 36 and 37 continue their downward movement, the bottle is distorted to the form shown in Fig. 3 of the drawings. In this condition of the bottle, the diametrically opposite body wall portions thereof, will assume the curvature of the seats 35 and 38; the seats by their confining action rigidifying such wall portions and the natural resiliency of the material of the bottle yieldingly resisting the downward relatively heavy pressure exerted by member 36 through its seat 38. During this phase of the operation, the label 27 will be firmly pressed in a uniform manner throughout its entire area by the heated seat 38 into engagement with the label receiving surface of the bottle and so that the final application of the label to the bottle is efficiently carried out. When the pressure member 36 is withdrawn, the bottle will return to its normal shape, thus withdrawing its distorted portions and the label from the surfaces of the seats 35 and 38. It will thus be seen that as a result of the configuration of the seats 35 and 38, there exists no danger that the flexible container will jam or lock when the applying pressure is removed and the pressure member 36 withdrawn. This disconformity of the seats 35 and 38 with the article should preferably not be too great or of sufficient divergence that the distortion of the article under the label applying pressure will damage the article. When the pressure member 36 has been fully withdrawn, the labeled bottle may be removed from the seat 35 and a new bottle substituted for the next succeeding cycle of the machine.

The shape of the seats in the support 11 and pressure member 36 may be brought into closer conformity with the bottle though not in exact conformity therewith for the reasons above mentioned, if during the label applying operation the article is filled with a fluid such as compressed air or water to temporarily rigidify the confined portion of the bottle to which the label is to be affixed under heavy pressure. This may be accomplished as shown in Fig. 4 of the drawings by attaching to the mouth of a bottle deposited on the support 11, a connecting member 45 capable of forming a substantially fluid-tight connection with such bottle mouth and provided on the end of a pipe 46 provided with a control valve 47. The pipe 46 is connected with a source of fluid such as compressed air or water under a pressure 75 greater than atmospheric. Thus, when the con-

nection member 45 is secured to the bottle and the valve 47 operated, the interior of the bottle will be filled with fluid under pressure and through the latter, the walls of the bottle will be sufficiently rigidified to withstand the pressure applied thereto by the member 36 during the final application of the label.

When bottles of the type previously described are to be labeled, the same result may be accomplished by exhausting the air from the interior of the bottle instead of filling it with fluid under pressure. In practicing this form of the invention, the top surface of the support 11" and the lower surface of the pressure member 36' are plain flat surfaces; the pressure member 36' being preferably also of an area slightly greater than the area of the label which is to be attached to the bottle, as is shown in Fig. 5 of the drawings. Instead of connecting the pipe 46' to a source of fluid pressure, it is connected to a source of vacuum so that when the connection 45' is attached to the bottle and the valve 47' operated, substantially all air will be exhausted from the bottle and the walls of the body thereof will collapse. Preferably, this operation is carried out while the pressure member 36' is squeezing the bottle 10 against the support 11", so that the escape of the air in the bottle will be facilitated and such escaping air will cushion, and at the same time, render more effective the pressure exerted by such member 36'. Instead of exhausting the air in the bottle to the extent shown in Fig. 5, the air in the bottle may be evacuated to a predetermined pressure or such that a sufficient portion of the surface area of the bottle conforming to the shape of the working face of member 36' is provided for attachment of the label thereto. At the end of the downward movement of the member 36', the parts will be in the condition shown in Fig. 5 of the drawings. The vacuum may be disconnected just prior to the upward return movement of pressure member 36' or may be maintained until after such member has completed its upward movement. Preferably, the valve 47 is a two-way valve, so that it may be operated to permit atmospheric air to enter the collapsed bottle 10 in controlled amounts.

While I have hereinabove described and illustrated in the drawings, preferred methods of carrying out the invention, it will be apparent to those skilled in the art that modifications and changes may be made therein without departing from the spirit of the invention or the scope of the appended claims.

I claim:

1. The method of labeling a flexible container having a flexible tubular side wall to which a label is to be applied, comprising adhering a label to the side wall of the container while the latter is in normal shape, then applying positive compressive pressure to the adhered label and the normally-shaped longitudinal part of said side wall to which the label has been adhered in a direction transversely to and toward the longitudinal axis of the article, continuing such positive compressive pressure to cause a substantial distortion of said side wall from its normal shape in directions transverse to such longitudinal axis, progressively finally attaching the label to said side wall while the latter is distorted under such continuing compressive pressure but not completely collapsed, continuing the progressive application of the label under such compressive pressure to such distorted side wall until the final attachment of the label is completed, and then

releasing the compressive pressure on said side wall to enable the latter to assume its normal tubular shape.

2. The method of labeling a flexible container having a flexible tubular side wall to which a label is to be applied, comprising adhering a label to the side wall of the container while the latter is in normal shape, then applying positive compressive pressure to the adhered label and the normally-shaped longitudinal part of said side wall to which the label has been adhered in a direction transversely to and toward the longitudinal axis of the article, retaining the label in initially attached position on said side wall by said compressive pressure, continuing such positive compressive pressure to cause a substantial distortion of said side wall from its normal shape in directions transverse to such longitudinal axis while retaining the label in its initially attached position on said side wall, holding the label in a shape different from the shape of the distorted side wall part to which such label is to be finally attached and substantially in the shape at which the attachment of the label to such side wall is to be completed during the continuance of such compressive pressure, progressively finally attaching the label to said side wall while the latter is progressively distorted under such continuing compressive pressure but not completely collapsed, continuing the progressive application of the label to such distorted side wall and the progressive distortion of said side wall under such compressive pressure until the final attachment of the label is completed, and then releasing the compressive pressure on said side wall to enable the latter to assume its normal tubular shape.

3. The method of labeling a flexible container having a flexible tubular side wall to which a label is to be applied, comprising adhering a label to the side wall of the container while the latter is in normal shape, confining the labeled part of said side wall within an area having a cross-section different from said side wall part in its normal shape, then while said side wall part is so confined applying positive compressive pressure to the adhered label and the normally-shaped longitudinal part of said side wall to which the label has been adhered in a direction transversely to and toward the longitudinal axis of the article, continuing such positive compressive pressure to reduce the confining area within which said side wall part is located and to cause a substantial distortion of said side wall from its normal shape in directions transverse to such longitudinal axis, holding the label in a shape different from the shape of the distorted side wall part to which such label is to be finally attached and substantially in the shape at which the attachment of the label to such side wall is to be completed during the continuance of such compressive pressure, progressively finally attaching the label to said side wall while said confining area is progressively reduced and while said side wall is progressively distorted but not completely collapsed under such continuing compressive pressure, continuing the progressive application of the label to such distorted side wall, the progressive distortion of said side wall and the progressive reduction of said confining area under such compressive forces until such compressive force is applied upon the entire surface of the label and the final attachment of the label is completed, and then releasing the compressive pressure on said side wall and expanding said confining area

to enable the side wall to assume its normal tubular shape.

4. The method of labeling a flexible container having a flexible tubular side wall to which a label is to be applied, comprising adhering a label to the side wall of the container while the latter is in normal shape, then applying positive compressive pressure to the adhered label and the normally-shaped longitudinal part of said side wall to which the label has been adhered in a direction transversely to and toward the longitudinal axis of the article, continuing such positive compressive pressure to cause a substantial distortion of said side wall from its normal shape in directions transverse to such longitudinal axis, progressively finally attaching the label to said side wall while the latter is distorted under such continuing compressive pressure but not completely collapsed, continuing the progressive application of the label under such compressive pressure to such distorted side wall until the final attachment of the label is completed, providing during the application of such compressive pressure and the progressive application of the label under such compressive pressure a controlled pressure within the interior of the container to coact with said compressive pressure in completing the final attachment of the label to the container, and then releasing the compressive pressure on said side wall to enable the latter to assume its normal tubular shape.

5. The method of labeling a flexible container having a flexible tubular side wall to which a label is to be applied, comprising partially adhering an intermediate part of a label to a longitudinally extending portion of the side wall part of the container to be labeled while the latter is in normal shape leaving the edges of the label on opposite sides of such intermediate part spaced from said side wall, then applying positive compressive pressure to the adhered label and the normally-shaped longitudinal part of said side wall to which the label has been adhered in a direction transversely to and toward the longitudinal axis of the article, holding the intermediate part of the label to the longitudinally extending portion of said side wall part by said compressive pressure, continuing such positive compressive pressure to cause a substantial distortion of said side wall from its normal shape in directions transverse to such longitudinal axis, attaching the label to said side wall while the latter is distorted under such continuing compressive pressure but not completely collapsed by simultaneously and progressively finally attaching the label on both sides of said initial line of attachment in an outward transverse fashion from such initial line of attachment, continuing such transverse progressive application of the label under such compressive pressure to such distorted side wall until the final attachment of the label is completed, and then releasing the compressive pressure on said side wall to enable the latter to assume its normal tubular shape.

6. In a machine for labeling flexible containers having a flexible tubular side wall to which a label is to be applied at an applying station thereof, means spaced from said applying station for supporting a supply of labels, means for delivering a label from said supply to said applying station and for adhering the delivered label to the side wall of the container while the latter is in normal shape, means for applying positive compressive pressure to the adhered label and the normally-shaped longitudinal part of said side

wall to which the label has been adhered in a direction transversely to and toward the longitudinal axis of the article, said applying means including a pair of spaced members having article engaging surfaces normally spaced a distance greater than the cross-sectional area of the article to be labeled and means for relatively moving said members toward each other to apply such compressive pressure to the adhered label and the article, said applying means being so constructed and arranged that when said spaced members are relatively moved from said normally-spaced condition a continuing compressive pressure is exerted thereby on the article to cause a substantial distortion of the side wall thereof from its normal shape in directions transverse to such longitudinal axis, to progressively finally attach the label to said side wall while the latter is distorted under such continuing compressive pressure but not completely collapsed, and to continue such progressive application of the label under such compressive pressure to such distorted side wall until the final attachment of the label is completed, and means for relatively moving said spaced members away from each other after the complete attachment of the label to enable the side wall of the container to assume its normal tubular shape.

7. In a machine for labeling flexible containers having a flexible tubular side wall to which a label is to be applied at an applying station thereof, means spaced from said applying station for supporting a supply of labels, means for delivering a label from said supply to said applying station and for adhering the delivered label to the side wall of the container while the latter is in normal shape, means for applying positive compressive pressure to the adhered label and the normally-shaped longitudinal part of said side wall to which the label has been adhered in a direction transversely to and toward the longitudinal axis of the article, said applying means including a first member having a surface for holding an article at said applying station, a second member provided with a label engaging surface normally-shaped a distance greater than the cross-sectional area of the article to be labeled from the holding surface of said first mentioned member and having an area at least as great as the area of the label adhered to the article, and means for relatively moving said members toward each other to apply such compressive pressure to the adhered label and the article, said applying means being so constructed and arranged that during such relative movement thereof a continuing compressive pressure is exerted thereby on the article to cause a substantial distortion of the side wall thereof from its normal shape in directions transverse to such longitudinal axis, to progressively finally attach the label to said side wall while the latter is distorted under such continuing compressive pressure but not completely collapsed, and to continue such progressive application of the label under such compressive pressure to such distorted side wall until the final attachment of the label is completed, the label engaging surface of said second member having such configuration that the label is held in a shape different from the shape of the distorted side wall part to which such label is finally attached and substantially in the shape at which the attachment of the label to such side wall is to be completed during the continuance of such relative movement of said members, and means for relatively moving said

spaced members away from each other after the complete attachment of the label to enable the side wall of the container to assume its normal tubular shape.

8. In a machine for labeling flexible containers having a flexible tubular side wall to which a label is to be applied at an applying station thereof, means spaced from said applying station for supporting a supply of labels, means for delivering a label from said supply to said applying station and for adhering the delivered label to the side wall of the container while the latter is in normal shape, means for applying positive compressive pressure to the adhered label and the normally-shaped longitudinal part of said side wall to which the label has been adhered in a direction transversely to and toward the longitudinal axis of the article, said applying means including a pair of normally-spaced members having article engaging surfaces, and means for relatively moving said members toward each other to apply such compressive pressure to the adhered label and the article, the surfaces of said members having such configuration that the labeled part of said side wall is confined within an area having a cross-section different from said side wall part in its normal shape, said applying means being so constructed and arranged that when said spaced members are relatively moved from said normally-spaced condition the confining area defined by the surfaces of said members is progressively reduced to cause a substantial distortion of said side wall from its normal shape in directions transverse to such longitudinal axis, to progressively finally attach the label to said side wall while the latter is distorted under such continuing compressive pressure but not completely collapsed, and to continue such progressive application of the label under such compressive pressure to such distorted side wall until the final attachment of the label is completed, the label engaging surface of one of said members holding the label in a shape different from the shape of the distorted side wall part to which such label is finally attached and substantially in the shape at which the attachment of the label to such side wall is to be completed during the continuance of such relative movement of said members, and means for relatively moving said spaced members away from each other after the complete attachment of the label to enable the side wall of the container to assume its normal tubular shape.

9. In a machine for labeling flexible containers

having a flexible tubular side wall to which a label is to be applied at an applying station thereof, means spaced from said applying station for supporting a supply of labels, means for delivering a label from said supply to said applying station and for adhering the delivered label to the side wall of the container while the latter is in normal shape, means for applying positive compressive pressure to the adhered label and the normally-shaped longitudinal part of said side wall to which the label has been adhered in a direction transversely to and toward the longitudinal axis of the article, said applying means including a pair of spaced members having article engaging surfaces normally-spaced a distance greater than the cross-sectional area of the article to be labeled and means for relatively moving said members toward each other to apply such compressive pressure to the adhered label and the article, said applying means being so constructed and arranged that when said spaced members are relatively moved from said normally-spaced condition a continuing compressive pressure is exerted thereby on the article to cause a substantial distortion of the side wall thereof from its normal shape in directions transverse to such longitudinal axis, to progressively finally attach the label to said side wall while the latter is distorted under such continuing compressive pressure but not completely collapsed, and to continue such progressive application of the label under such compressive pressure to such distorted side wall until the final attachment of the label is completed, means providing a controlled pressure within the interior of such container during such relative movement of said members and coaxing with the latter to complete the final attachment of the label to the container, and means for relatively moving said spaced members away from each other after the complete attachment of the label to enable the side wall of the container to assume its normal tubular shape.
